HIGH INTENSITY LAMP

Harold S. Boutin, Northwood, Ohio (31217 Fostoria
Road, Rte. 2, Box 238, Curtice, Ohio 43412)

Filed Jan. 24, 1966, Ser. No. 727

Term of patent 14 years

(Cl. D48—20)

FIG. 1 is a perspective view showing a high intensity lamp embodying my design;

FIG. 2 is a front view of the lamp shown in FIG. 1;

FIG. 3 is a side view of the lamp shown in FIG. 1; and

FIG. 4 is a rear view of the lamp shown in FIG. 1.

I claim:

The ornamental design for a high intensity lamp, as shown.
